UNITED STATES PATENT OFFICE.

JESSE W. HAYES, OF BALTIMORE, MARYLAND, ASSIGNOR OF ONE-HALF TO LOUIS STEPPACHER, OF BALTIMORE, MARYLAND.

COMBINED PENCIL-HOLDER AND INHALER.

973,427.

Specification of Letters Patent. Patented Oct. 18, 1910.

Application filed August 17, 1909. Serial No. 513,279.

To all whom it may concern:

Be it known that I, JESSE W. HAYES, a citizen of the United States, residing at Baltimore city, State of Maryland, have invented certain new and useful Improvements in a Combined Pencil-Holder and Inhaler, of which the following is a specification.

My invention relates to an improvement in combined pencil holders and inhalers, and particularly to inhalers of the portable or pocket type containing a medicament for the cure of catarrh and kindred ailments, or such other inhalant as may be desired; and it consists in the novel and simple combination and construction of a pencil holder and inhaler, and in the new and novel arrangement and combination of its parts, as will hereinafter be more fully described and set forth.

20 The further object of my invention being to provide a convenient, simple and effective device which may be closed when used as a pencil holder and out of use as an inhaler, so as to prevent the evaporation of the volatile medicinal substance with which the device is charged, and which may be readily opened when desired to be used as an inhaler, so that when applied to the anterior nares for use, an inflow of medicated vapors will be caused.

25 With the foregoing objects in view, my invention consists in certain novel features of construction and combinations of parts, which will be hereinafter described and 30 pointed out in the claim.

In the accompanying drawings, forming a part of this specification, Figure 1 is a longitudinal view of the inhaler, the same being in closed position; Fig. 2 is a view 40 similar to Fig. 1, but, with the parts in position to be used as an inhaler; Fig. 3 is a perspective view of the medicated cylinder and plunger attached thereto; and Fig. 4 is a view partly in elevation and partly in section, showing a modified form of medication.

A, represents an ordinary pencil, slidably secured on the end of which is provided a tubular barrel 1, forming the holder; the 50 barrel may be made from any suitable material, but preferably of metal; and is provided with an opening 2, in the upper end thereof. Within the wall of the barrel, located a predetermined distance from the 55 lower end portion thereof, is provided an

additional opening 3. Secured within the barrel a predetermined distance from the upper end portion, by frictional contact with the inner walls thereof, is a cylinder 4, made from any suitable absorbent material, but 60 preferably of paper pulp, adapted to absorb and retain a medicament.

Secured within the cylinder and reciprocable thereof, is provided a rod 5, on the ends of which are provided disks 6 and 7 respectively, the disk 7 having a packing 8, made from any suitable material, such as a piece of felt, secured thereon, the purpose of which will be hereinafter described.

My device is operated as follows: As 70 shown in Fig. 1, the barrel 1 performs the functions of an ordinary pencil holder, the use of which being so well known to those skilled in the art to which it appertains, as to demand no further explanation here. As 75 shown in Fig. 1, the pencil A, is inserted within the barrel 1 a predetermined distance, engaging with the disk 6, on the lower end of the rod 5, thereby forcing the rod upward, and causing the disk 7 on the upper 80 end thereof to close the opening 2 in the end of the barrel, the packing 8 on the disk 7, serving to insure a tight closure. At the same time the pencil A, being extended past the opening 3 in the barrel serves to close the 85 said opening, thereby sealing the barrel and preventing the evaporation of the medicament of which the cylinder may be either composed or supplied.

When it is desired to use the device as an 90 inhaler, the pencil A is withdrawn from the barrel 1 past the opening 3, the pencil at the same time disengaging the disk 6, causing the rod 5 to descend, and release the disk 7, from the opening 2 in the barrel, as 95 shown in Fig. 2, and when in this position the medicated vapors from the cylinder will flow through the opening 2 in the barrel, the inhaler now being open and ready for use.

In Fig. 4, I have shown a modified form 100 of cylinder, indicated 9, the cylinder in this instance being composed of a medicament, some medicaments owing to their solidity being capable of being formed into a cylinder 105 suitable for this purpose, while others owing to their insolubility, are not capable of such formation.

Slight changes and alterations might be resorted to in the form and arrangement of 110

the several parts described, without departing from the spirit and scope of my invention, and hence I do not wish to limit myself to the exact construction herein set forth; but,

5 Having fully described my invention, what I claim as new and desire to secure by Letters Patent, is:—

An article of the character described, 10 comprising a barrel having an opening at one end coextensive in diameter with the interior diameter of said barrel, having a reduced opening at its other end, and having an opening in its side intermediate its 15 length, a cylinder secured within said barrel between said reduced and side openings,

a rod reciprocable within said cylinder, disks on the ends of said rod one of which is adapted to close said reduced opening in said barrel from the interior, and means 20 removably inserted in the other end of said barrel and adapted to shift said rod by contact with its disk at that end to cause its other disk to close said reduced opening, said means also adapted to cover and un- 25 cover the side opening in said barrel.

In testimony whereof I affix my signature in presence of two witnesses,

JESSE W. HAYES.
